UNITED STATES PATENT OFFICE.

JACOB GERRITSON, OF KANKAKEE, ILLINOIS, ASSIGNOR, BY MESNE ASSIGNMENTS, TO PARAMOUNT TEXTILE CO., OF CHICAGO, ILLINOIS, A CORPORATION OF ILLINOIS.

HOSIERY DRYING AND SHAPING STRUCTURE.

Application filed September 13, 1919. Serial No. 323,599.

To all whom it may concern:

Be it known that I, JACOB GERRITSON, a citizen of the United States of America, residing at Kankakee, in the county of Kankakee and State of Illinois, have invented certain new and useful Improvements in Hosiery Drying and Shaping Structures, of which the following is a specification, reference being had therein to the accompanying drawing.

This invention has reference broadly to hosiery drying and shaping structures, and resides more specifically in a holding device which is attachable thereto and subserves the function of preventing the natural shrinking or creeping of the hosiery while the moisture therein is being evaporated when drying.

The present invention constitutes an improvement upon and advance over the device disclosed in United States Patent No. 1,320,753, dated November 4, 1919, for improvement in hosiery drying and shaping structures. The structure of that case includes a slotted base member, (preferably made of asbestos paper), a hosiery-engaging member (preferably having a pile) which has its edge-portions extending through the slits of the base member, and a backing member (preferably of asbestos paper) interposed between the backing member and the hosiery-engaging member. In this instance, the pile extends over the entire area of one surface of the member, wherefore when its edge-portions are inserted through the slits in the backing member, the pile-carrying edge-portions underlie the under-face of the backing member. In manufacturing this device, it has been found that the pile of the edge-portions makes it difficult to secure such edge-portions to the backing member and, besides, it tends to make the device too thick so that, when mounted upon a hosiery drying and shaping form, the device (in its entirety) has too much bulge, and this tends to unduly stretch the fabric of the hosiery at the point where it is engaged by this holding device. In addition, the interposed fabric-distending member also tends to make the device too thick and bulky, and considerably adds to the cost of manufacture.

The present invention is predicated upon the discovery that, if the edge-portions of the hosiery-engaging fabric are formed as a

selvage and without any pile thereon, these selvage portions are more conveniently inserted through the slits in the backing member and may be more securely cemented to the backing member and also to the form when the device is applied thereto. Besides, the section of the backing member between the slits, by reason of the fact that these slits extend longitudinally of the backing member, in contradistinction to extending transversely thereof as in the structure of my aforementioned pending application, tends to distend the fabric of the hosiery-engaging member sufficiently to cause it more efficiently to engage and hold the hosiery while the latter is on the form drying. Another feature of difference between the two devices is the fact that, in that of the present invention, the paper backing member has applied to one surface thereof a sheet of fabric so that the section between the slits will receive and hold the cement by which the fabric member is secured to the paper backing member and cement these two members together effectually.

In order that the invention may readily be understood, both as to its structure and as to the manner in which it is applied to a drying and shaping form, I have illustrated a preferred type thereof in the accompanying drawings; but it is to be understood that these drawings are merely illustrative and that the type shown is susceptible of a wide range of modification and variation without departure from the spirit of the invention and without sacrificing any of its underlying and salient principles.

In the drawings:

Figure 1 is a view in elevation of a drying and shaping form with the improved fabric hosiery holding device mounted thereon;

Fig. 2 is a view, on a larger scale, in transverse section, on the line 2—2, Fig. 1;

Fig. 3 is a view in top plan of the hosiery holding device, complete and detached from the form;

Fig. 4 is a similar view of the reverse side of the holding device;

Fig. 5 is a view in transverse section, on the line 5—5, Fig. 3;

Fig. 6 is a view of the backing member, by itself;

Fig. 7 is a similar view of the selvage-provided hosiery-engaging member;

Fig. 8 is a fragmentary view, in longitudinal section, of the holding device applied to a form; and

Fig. 9 is a fragmentary view, in transverse section, of the holding device mounted on a form and with a portion of a stocking overlying and engaged by the holding device.

In these drawings, the reference-numeral 10 1 designates a so-called "Paramount" hosiery drying and shaping form as constructed and exploited under U. S. Patent No. 1,207,496, granted December 5, 1916. This form is hollow to contain a heating medium 15 whereby heat is thereby applied to the internal surface of the fabric of the hosiery, designated generally by the reference-numeral 2. This form has fabric-smoothing and flattening sides 3 which, in this instance, 20 are shown as arc-shaped and as merging into reduced or crease-forming edges 4. The form, itself, is provided with a base 5 by which it is mounted upon a pipe 6 for conducting a suitable thermal fluid to the interior 25 of the form from a suitable source of supply.

Mounted on opposite sides of this form, and at a suitable or predetermined distance from the base 5, is my fabric-holding device 30 7, each of these being, preferably and as shown, of less width than that of the form 1 in order that the oppositely-disposed devices shall not entirely encompass the form. The longitudinal dimensions of each device 35 are dictated by the amount of fabric-engaging surface which is to be presented to the hosiery, this being, in a large measure, dependent upon the character of the goods being treated: Some fabrics have a greater 40 tendency to shrink while drying than others, and the amount of moisture in the fabric varies in different mills, since some manufacturers find it desirable or preferable to extract less moisture, (by the whizzer) than 45 others. On the other hand, some hosiery fabrics—such, for instance, as woolen goods—hold their moisture in greater quantity than others.

The preferred type of device is shown, as 50 a complete embodiment, in Figs. 1 to 5, 8 and 9: As there illustrated, the device includes a base or form engaging member 8. This member is provided, adjacent its edges, with two elongated slits or slots 9 of appropriate dimensions. This member is preferably made of a sheet of fire-and-damp-proof asbestos paper that has, by preference, been treated with a suitable sizing or similar substance, such for instance, as a liquid or 55 pasty flour composition. Cemented or otherwise secured to one face of this paper member is a covering sheet 10 preferably of cambric or similar material, and which is slitted, as at 11, to correspond with the slits 60 9 in the paper member 8.

The holding device also includes a hosiery-engaging and holding element 12, composed of a pile portion 13—that is, a portion formed with a pile—and with edge or selvage portions 14 unprovided with pile 70 and which I shall hereinafter refer to as "selvage portions", "plain portions", and equivalent expressions. The pile is of a character to smooth down flat when rubbed in one direction and, when rubbed in the 75 other direction, tends to stiffen, stand out, and offer more or less reaction or resistance. This instrumentality, during the "boarding" operation, permits the hosiery to be placed on the form without difficulty or 80 discernible friction. But, the moment that the down-stretching motion on the hosiery (during the "boarding"-operation) ceases, the pile 13 effectually engages the fabric and prevents it from shrinking or creeping upwardly so that, as the hosiery drying form tends to dry and shape the article, my improved hosiery-holding device efficiently retains it in its stretched condition until the 85 fabric of the hosiery is set and given a "fixed" condition. This pile-provided member 12 is of less width than the member 8, as shown, and has its plain or edge-portions of selvage extended through the slits or slots 9 and secured against the underside 90 or face of the member 8, the plain portions 14, thus, underlying the sections 15 of the paper member 8 beyond the slits 9 therein.

The central portion 13 of the fabric member 12 overlies the central portion 16 of the member 8 and is secured to the section of the cambric sheet 10 which covers the section 16.

The central section 16 of the member 8, with the cambric covering thereon, gives to that section a thickness sufficient to distend or raise the pile-covered portion of the fabric member 12, as shown in a somewhat exaggerated manner in Figs. 5, 8 and 9. Thus, the pile is able to perform its holding function throughout its entire exposed area; and yet the thickness of the entire device at that portion is not sufficient to be bulky and unduly stretch the fabric of the hosiery 110 during the "boarding" operation.

The paper member 8, with its cambric covering 10, and the hosiery holding member 12 are bound together—to constitute an article of commerce—by a cementitious substance, such as water glass, or a substance which includes silicate of soda. In addition to the fact that this water glass constitutes an effective cement for securing the device to the form, it also possesses the desirable characteristic of being a good conductor of heat. It will now be understood that my device, as an article of manufacture, includes the backing member 8, preferably carrying the fabric holder 10, and slitted as at 9, combined with the fabric member 125 130

12 having the pile portion 13 and selvage or plain portions 14, the pile portion overlying and secured to the central section 16 of the member 8 and having the selvage portions 14 extended through the slits 9 so that these selvage portions underlie the outlying sections 15 of the member 8; and that this article of manufacture is secured, as by water glass, to a hosiery form so that the 10 outlying portions 15 of the member 8 are cemented to the form, the underlying selvage portions 14 also being cemented to the form, and the central portion 16 being similarly cemented to the form. But the effective, pile-carrying portion of the member 12 is insulated (so to speak) from the form by the central section 16 of the member 8. In other words, the outstanding sections 15, the insulating section 16, and the end 20 section 17, of the member 8 lie against and are secured to the form; and, likewise, the selvage or plain portions of the fabric member 12, while the central or pile-carrying portion 13 of the fabric member 12 is elevated away and spaced from the form by the central portion 16 of the member 8.

The form-engaging member 8, being of asbestos material, is more or less a non-conductor of heat, whereas the covering-sheet 30 10, being of fabric, is a conductor of heat; hence, while the form-engaging member protects the hosiery-engaging element 12 at its central portion against destructive heat-action, nevertheless, the covering-sheet 10, 35 while protecting and reenforcing the edge-portions of the member 8, has no normal tendency to prevent heat from the form 1 being transmitted to the portions of the hosiery overlying the covering-sheet and, 40 thus, drying of the hosiery is thereby facilitated. Moreover, the covering-element 10, being of fabric and, thus, of a material different from that of the backing-member 8, has a normal tendency to prevent wear of 45 the exposed portions of the backing-member, as by friction caused during the placing of a damp stocking on the form and the removal of the dried stocking therefrom.

In mounting the device upon the form, 50 the cementitious mass—such as the water glass—may if desired be spread over the upper surface of the exposed portions 18 of the fabric-covering 10.

From the foregoing, it will now be manifest that I have provided an effective hosiery holding device which is conveniently and quickly applied to a form—preferably while heated—and which is very endurable and wear resisting under the naturally destructive action of the boarding operation. The 55 pile, by reason of the fact that it stands out

practically throughout its entire area, has an effective holding surface of a greatly increased capacity. By using the fabric-covering 10, the paper member 8 may be of 65 relatively thin material. In consequence of these factors, the cost of manufacture of this device is appreciably reduced and without affecting the holding characteristics of the device in any way, since it has been found in 70 practice that hosiery, treated on a form to which my device is applied, has an improved finish by reason of the fact that the device effectually holds the hosiery in intimate contact with the form during the time that the 75 fabric of the hosiery is evaporating its moisture and while being “set” in the condition into which it has been stretched by the holder. Thus, the hosiery “finishes” at a uniform length because the device effectually precludes creeping or shrinking longitudinally while on the form.

What I claim is:

1. A holding-device for hosiery-drying and shaping forms including a relatively 85 thin backing-member of heat non-conducting material provided with slits, a fabric hosiery-engaging element having its central portion overlying the section between the slits of the backing-member and its edge-portions underlying the sections thereof beyond the slits, and a fabric member-covering of heat-conducting material overlying said edge-portions; the backing-member constituting an encompassing frame for the 90 hosiery-engaging element to protect its edges; and the hosiery-engaging element and member-covering, together, presenting a fabric facing for the backing-member approximately coextensive with the surface dimensions thereof.

2. A holding-device for hosiery-drying forms, including a backing-member, a hosiery-engaging element comprising a pile-portion and a plurality of selvage-portions 105 unprovided with pile, and a member-protecting covering of textile fabric secured to the backing-member; the hosiery-engaging element and covering presenting a facing for the backing-member approximately co-extensive with the face thereof; and the pile-portion of the engaging-element being relatively thicker than its selvage-portions and having its pile extending beyond the plane of the covering.

In testimony whereof I affix my signature in presence of two witnesses.

JACOB GERRITSON.

Certificate of Correction.

It is hereby certified that the assignee in Letters Patent No. 1,485,385, granted March 4, 1924, upon the application of Jacob Gerritson, of Kankakee, Illinois, for an improvement in "Hosiery Drying and Shaping Structures," was erroneously described and specified as "Paramount Textile Co.," whereas said assignee should have been described and specified as *Paramount Textile Machinery Co.*, as shown by the records of assignments in this office; and that the said Letters Patent should be read with this correction therein that the same may conform to the record of the case in the Patent Office.

Signed and sealed this 1st day of April, A. D. 1924.

[SEAL.]

KARL FENNING,
Acting Commissioner of Patents.
